GRAIN DISTRIBUTOR

Roy L. Patterson, Minneapolis, Minn.

Application December 10, 1945, Serial No. 634,026

8 Claims. (Cl. 193—23)

1

My invention relates to grain distributors and has for its object to provide, in combination of one or a plurality of leg spouts running from the elevating leg or legs of an elevator, novel and highly efficient means of transferring grain from said leg spouts to any selected one of a large number of outlet members discharging respectively into bin spouts leading to a corresponding number of bins in the elevator, not shown.

Efforts heretofore made to provide a distributor of the type covered herein by my invention, wherein the transfer delivery spout is rotated about a vertical axis, have not proved successful because of the tendency to clog and difficulties in effecting rotation and adjustment of the discharge end of the distributor spout to the receiving ends of the bin spouts. There also has been grave difficulty with this type of distributor because when a bin would become filled the distributor ducts would in turn be filled up clear back into the head of the leg and great difficulty, loss of time and spillage of grain would result from attempts to clear the same.

I have discovered a way of mounting the rotating distributor spout in relation to a novel shoe or outlet member such that the adjustment of the transfer spout or spouts, whether 1, 2, or 3 or any number of such spouts are employed, may be easily effected with absolute certainty and with no danger of clogging. Further, that if the bin becomes filled and tends to back up to the distributor itself the excess grain will automatically be transferred to the loading point at the bottom of the leg elevator boot.

I further discovered that it is practical and produces exceptionally satisfactory results to build the cylinder in two sections, the lower section supported from the upper section and having the adjacent edges spaced apart to leave an open annular portion; and to mount removably in said open annular portion a surrounding set of outlet members which are held in position by drawing together the edges of said cylinder sections and which thus may readily be removed at any time for replacement and repair.

It is an object of my invention, therefore, to provide a circular distributor cylinder having a central transfer pipe and a surrounding annular transfer pipe or pipes, all provided with discharge openings facing an elongated boot or outlet member such that grain from one or more of said transfer pipes will go certainly and without spillage into the outlet member and thence into the bin spouts.

It is a further important object of my inven-

2

tion to form the distributor cylinder in two sections and to secure them together, with an annular space between the adjacent edges, by means of outer rods so that said annular space may be varied in width and may receive and removably hold all the outlet members employed in my device.

It is a further object of my invention to mount the one or more transfer spouts in the casing so that it or they may be uniformly and easily rotated, with connections for rotating them located at a distance from the receiving member and with means for certainly and fixedly locking the rotated members in position to discharge grain to a selected spout.

It is a further object of my invention to provide means in the casing for elimination of air pressure by permitting exhaust of air from the enclosing casing, said exhaust air carrying dust and fine matter entering the casing with the grain and discharging it outside of the building.

It is a further object of my invention to provide in combination with my distributing device means for receiving overflow from any bin spout when the bin has become filled and collecting it and returning it to the point of initial elevation.

Further objects of my invention are to provide a member wherein the parts may be readily removed for repair or replacement, which is light and inexpensive to build, and which may readily be installed in any elevator.

In the drawings illustrating an application of my invention in some of its forms:

Fig. 1 is a top plan view of my distributor with the top cover removed showing the frame support for the parts thereof.

Fig. 2 is a sectional elevation view taken on line 2—2 of Fig. 1 except that the showing of outlet members has been eliminated to show more clearly the space between adjacent edges of the parts of the distributor cylinder.

Fig. 3 is a sectional plan view taken on line 3—3 of Fig. 2.

Fig. 4 is an enlarged detail of the means of locking the rotating part or parts in fixed position.

Fig. 5 is a longitudinal sectional view of a device embodying my invention with only one spout therein.

Fig. 6 is an enlarged semi-plan view taken on line 6—6 of Fig. 5.

Fig. 7 is a sectional elevation view showing my invention as applied to three discharge spouts.

Fig. 8 is an enlarged detail view of the manner of support for the rotating members.

Fig. 9 is a schematic drawing showing some parts in section and particularly showing the means for rotating the transfer spout members and for locking the parts in operative position.

Fig. 10 is an enlarged sectional elevation view on line 10—10 of Fig. 1, but showing only a fragmentary part of the upper portion of the distributor.

Fig. 11 is an enlarged detail view showing the manner of adjustably mounting the roller for supporting the rotating spout member.

Fig. 12 is a top plan view of a quarter of the distributor shown in Fig. 7.

As illustrated, my invention comprises an upper cylindrical casing 12 which is closed at its upper end by a top plate 13 having apertures therein as will be later pointed out.

The cylinder 12 is supported within a rectangular frame 14, Fig. 1, embodying side rails 15, 16, 17 and 18 which are riveted to the cylinder at their central points as indicated at 19, 20, 21 and 22. The several members 15, 16, 17 and 18 are integrally united at their respective corner junctions either by being formed of a single band of material, by welding or in any suitable way to make this rectangle a rigidly inter-connected integral member.

The upper ends of angle iron supports 23 and 26 are rigidly secured by welding or other means to the transverse frame member 15, and the upper ends of angle irons 24 and 25 are integrally united with the transverse frame bar 17, all as shown in Fig. 1. The lower ends of members 23, 24, 25 and 26 are secured by welding or otherwise to four plates 27, 28, 29 and 30 which are shown in Fig. 3 secured to the floor, indicated at 31, of any room as in the loft of an elevator, grain receiving room, packing room and the like. This securing is effected by screws 32 in a customary manner.

By this means the cylinder 12 and all parts carried thereby or connected thereto are supported upon the floor of the elevator loft at a suitable distance from the upper floor level.

Across the top of the cylinder 12, as shown in Fig. 1, are secured two sets of bars or transverse structures 33 and 34 and 35 and 36 respectively. These members have flanges riveted to the cylinder 12 as indicated at 37 in Fig. 1 and are set together at their crossing points and firmly united at these crossing points indicated as 38 so as to form a firm transverse supporting framework.

A brace member 39 extends between struts 33 and 35. Another brace member 40 extends between struts 34 and 35. A brace member 41 extends between struts 34 and 36 and a brace member 42 extends between struts 33 and 36. All these parts are held rigidly united together to form a strong and rigid transverse supporting framework, as clearly shown in Fig. 1.

A lower cylinder 12a, of the same diameter but spaced from cylinder 12, has its bottom open and is surrounded by an annular strengthening member 43. United as by welding or other means at the bottom edge of cylinder 12a is a supporting ring 44, Fig. 2. This ring will preferably be made of iron rod of a suitable diameter formed into a circular ring.

A hopper 45 having a central outlet 46, of customary cone shape, is provided with a ring 47 similar to ring 44, which ring 47 is attached to the upper part of the hopper at a point slightly removed from its upper edge 48, as indicated at 49 in Fig. 2. The ring 47 is both a strengthening and a supporting member for holding the hopper 45 for ready removal from the distributor.

Thumb screws 50 threaded through the wall of cylinder 12a are adapted to engage substantially the outer edge of hopper 45 to position it relative to its axial center, while the supporting ring 47 engages supporting ring 44 and holds the hopper in fixed operative position. To remove the hopper it is only necessary to loosen screws 50 and compress the upper edge of the hopper and the supporting ring 47 slightly, whereupon, by tipping the hopper at an angle, it may readily be removed. The purpose and use of this hopper will be hereinafter given.

The cylinders 12 and 12a are operatively a complete cylinder from the top 13 to the bottom support at the supporting ring 44, even though in effect divided into two parts. The lower part, as in Figs. 2 and 5, is designated 12a, and as in Fig. 7, 12b. These two cylinder parts have the lower edge 51 of cylinder 12 separated from the upper edge 52 of cylinder 12a or 12b. This space is well shown in Fig. 2 indicated by the numeral 53, since in Fig. 2 the intervening outlet members have not been shown.

Fig. 2 in conjunction with Fig. 1, shows how these portions of the cylinder 12 and 12a are adjustably supported for receiving and supporting the outlet hoppers. The support is made by four rods 54, 55, 56 and 57, the ends of which are shown in Fig. 1. While I have shown four rods, it will be understood that a greater or less number of rods may be employed, according to the size of the entire distributor and the use to which it is to be put.

Each of these rods is threaded at its upper end 35 and extends through an opening in a casting 58, which has an extension 59 rigidly secured by welding or otherwise to the walls of cylinder 12. This casting and the manner of securing the same, being the same for each of the rods 54, 55, 40 56 and 57, will not be further described excepting to point out that they are relatively long in extent and have a long opening indicated in dotted lines at 60 on Fig. 2, which receives the several rods 54, 55, 56 and 57, respectively, and holds them in rigid alignment parallel with the walls 45 of the cylinder 12.

The lower ends of each of these rods pass through a casting 61 which has an extension 62 rigidly connected with the wall of the cylinder 50 12a (or 12b). This casting also is provided with a long opening indicated in dotted lines at 63 for receiving the rods 54, 55, 56 and 57, respectively. The lower ends of these rods are shown threaded, with a nut 64 thereon, but it is not necessary to have a nut applied to the lower ends 55 of the rods, as they may have an ordinary bolt head or even be welded into position on the cylinder portion 52.

The upper ends of the rods 54, 55, 56 and 57 are 60 threaded and have applied to the threaded ends thereof, above the respective castings 58, a nut 65. It is obvious that by turning the nuts 65 the cylinder section 12a, or 12b, may be drawn up to narrow the space 53 between edge 51 of cylinder 12 and edge 52 of cylinder 12a. Within this space are mounted the several outlet members 65 designated generally, in the form of the invention of Figs. 2, 5 and 6, by the numerals 66 and 66'. Each of these members comprises parallel side walls 67 and 68, a short sloping bottom wall 69 and a long sloping top wall 70, all leading to an elongated discharge opening 71.

As shown in Fig. 5, the upper edge of the top wall of outlet member 66 is turned at an angle 75 to produce a flange 72 which is curved and

adapted to lie against the inner surface of the lower part of cylinder 12. The short sloping edge 69 is formed at its upper edge with a V-flange 73 which is adapted to take over the upper edge 52 of the lower cylinder section 12a.

These outlet members are, therefore, adapted to be removably positioned within the space 53 by supporting them by V-flange 73 over the edge 52 of lower cylinder 12a and bringing the upper flange 72 against the inner wall of cylinder 12. Markers 74, Fig. 6, may be employed properly to position the long opening 75 of the outlet hopper 66' in this space to receive discharge as later pointed out.

The several outlet members 66 (and 66' and 115) are so proportioned that when a full complement thereof have been positioned in the annular space 53 they will completely fill that space and form a circle of outlet members contacting the edge portions bounding the annular space 53.

In the form of the invention here shown in Figs. 1 and 2 there will be sixteen of said outlets, but obviously a greater or less number of outlet members may be employed, as in the simpler form of Fig. 5, where there will be only 8 or 10 outlet members.

At the points where the inner edges of side walls 67 and 68 of the members engage they will be fastened together by bolts 76, as indicated in Fig. 6. Two bolts are shown in the form of Fig. 5, while three bolts are shown in the form of Fig. 2 and four bolts in the form of Fig. 9. But it will be clear that a sufficient and not excessive number of bolts may always be employed.

In the form shown in Fig. 5, for a single distributor transfer spout the flange 72 will extend directly from the edge of top wall 70. In larger forms such as shown in Figs. 2 and 7 the flange 72 will extend at right angles to an extension 77 turned inwardly from the upper edge of top wall 70.

When the entire circle of outlet members have been positioned about the space 53 between edges 51 and 52 of the upper and lower cylinder members 12 and 12a, the entire assemblage will be locked together by turning down on nuts 65 of bolts 54, 55, 56 and 57, or any number of such bolts which may be used. This brings these edges in firm clamping engagement with the upper and lower respective walls of the outlet members and firmly locks the entire assemblage in position thereon.

Taking up the simplest form of distributor shown in Fig. 5, where a single distributor transfer spout is used, an opening 78 is formed at the center of the top member 13 and is provided with a cylindrical downwardly turned extension 79. This opening through downwardly turned extension 79 will receive the end of discharge spout 80 from an elevator leg, thus being adapted to have the stream of grain lifted by the elevator leg discharged from the spout 80 and through the extension 79.

A spout member 81—as shown an open-topped spout member, is provided with a cylindrical portion 82 which extends freely and loosely about the extension 79 from leg spout 80. The bottom wall 82 of spout 81 is extended angularly, as indicated in Fig. 5 to its discharge opening at 83, which comes directly opposite an opening 75 of an outlet member 66. The opening 83 is, however, presented to the upper part of opening 75, and the bottom 82 of spout 81 is cut away at 84 for a purpose later to be described.

A vertical shaft 85 is provided at its upper end with a plate 86 which is secured by welding, riveting or in any suitable manner to the bottom 82 of spout 81, thus being made a rigid attachment thereto. The shaft 85 will preferably be a tube or pipe. The lower end thereof, as shown in Fig. 8, is provided with a pin 86 which extends into the interior of the tube formed by shaft 85 and is riveted thereto, as indicated at 87.

Fast on the pin 86 and adapted to rotate with it and with shaft 85 is the upper part 88 of a thrust ball bearing, the lower part 89 of which is supported upon a circular base indicated at 90 and 91. This circular base is secured to and supported upon a spider made up of radiating bars 92, Fig. 3. The shaft 85 and the spout 81 connected thereto is, therefore, free to rotate freely about a vertical axis which is supported by thrust bearing 88, 89 and cylindrical extension 82 about depending cylindrical extension 79.

In the form of the invention of Figs. 1 and 2, there are means for carrying grain from the first indicated leg discharge spout 80 and also from a second leg discharge spout 93. The discharge spout 80 in this form enters a tubular extension 94 similar to extension 79 heretofore described, excepting that it is much longer. The extension 94, however, surrounds the circular central opening 78 in the top 13. A transfer spout 98 is provided with an angular extension 96 which is rotatable about pipe 94 by a movable joint 97.

The bottom wall 100 of pipe 98 has secured thereto by riveting or otherwise the same plate 86 at the top of tubular supporting member 85. In order, however, to brace the lower end of pipe 98 (and also of pipe 82) and the other parts carried therewith, a brace rod or bar 101 extends from the tubular shaft member 85 to the lower end of pipes 82 and 100.

Pipe 100, as is true of spout 81, is provided with a cut-out portion 84 at its bottom.

The support of the single pipe 98 which connects with the tubular extension 94 into which the leg outlet pipe discharges is thus made directly upon the tubular shaft 85 and rotates upon it as an axial center to take facing position opposite any selected outlet hopper 66'.

The spout 93 discharges into an annular passageway 102, Fig. 2, which has a central tubular portion 103 that surrounds the extension 94. Annular passageway 102 has a sloping wall 104 which surrounds the pipe 94, as indicated in dotted lines at 105 and runs into an extension 106 of said sloping passageway. The annular passageway 102 opens at 107 into a transfer pipe 108 having the sloping extension 106 as its bottom wall, and having an opening 109 which is presented to any of the openings 75 in any of the outlet members 66'. The plan view form of transfer spout 108 is shown at 108' in Fig. 9.

In the form of the invention shown in Fig. 7 there is a central pipe 110 which is somewhat longer than the central pipe 94, and which has its end surrounded by a cylindrical extension 111 at the end of a sloping pipe 112 which has an opening 113 fronting an elongated opening 114 in an elongated outlet member 115. The pipe 112 has its floor 116 sloping down to the lower part of opening 114 at the face of outlet member 115, and said sloping wall 116 is cut away as indicated at 117 for a purpose later to be described. There is also an annular passageway 118 which is formed with a central tubular opening 119 which surrounds the tubular extension 110 and which 75 connects with the discharge leg spout 83.

The annular passageway 118 has a sloping floor 120 which is joined to the outer walls 118' and the inner wall 119 and is coaxial to the extension 110. The floor 120 extends to a part 121 which is at the bottom of a transfer pipe 122 having an opening 123 facing the opening 114 of the outlet hopper 115. The leg spout 93 discharges into the annular passage 118 through opening 124. A third annular transfer passageway 125, Fig. 7, is comprised of a cylindrical casing 126 which forms the outer boundary of the annular transfer passageway 118. The casing 118' forms the inner boundary of the annular passageway 125 which has its upper edge 127 substantially lower than the upper edge 128 of the cylindrical casing 119', for a reason which will later be given.

The annular transfer passageway 125 has a sloping floor 129 indicated in dotted lines at 130 as extending about the cylindrical casing 119', said floor running into an extension 131 which forms the bottom wall of a discharge transfer spout 132 that has its opening 133 presented to the extended vertical opening 114 of any outlet member 115, all as shown very clearly in Fig. 7.

A third leg spout 134 goes through an opening 135 in the top member 13 and discharges into the upper part of the annular passageway 125.

A detail of the support for the annular members 102 and 118 and the parts carried by them is shown in Fig. 10 and the means of support is also shown in Fig. 1.

At the center of each of the brace rods 39, 40, 41 and 42 shown in Fig. 1, is secured a hanger arm 136. In each case this arm has thereon a threaded pin 137 having secured thereto a bearing 138, shown in dotted lines in Fig. 11.

Upon this bearing 138 is mounted a roller 139. Upon the upper end of the cylinder 119' forming the annular passageway 118, are rigidly affixed a pair of supporting rings 140 and 141 spaced apart a distance slightly greater than the diameter of the roller 139, and the rollers 139 come between these rings 140, 141, as clearly shown in Fig. 10. By this means the annular passageway formed between walls of the concentric cylinders 118' and 119 and all the parts connected therewith, including the transverse spout 122, are supported for free rotation from the brace bars 39, 40, 41 and 42.

The position of the roller 139 relative to the channel between the rings 140 and 141 may be accurately set by the adjustment provided for, as indicated in Fig. 11. The hangers 136 are provided with longitudinal slots indicated in dotted lines at 142 of Fig. 11. The threaded bolt 137 passes through that slot and has mounted thereon oppositely threaded nuts 143 and 144. By loosening these nuts and sliding them with the threaded stem 137 up or down, the vertical position of the roller 139 may be satisfactorily adjusted, and by releasing one and screwing up on the other of nuts 143 and 144 the roller may be drawn in or out and adjusted horizontally so as to take a perfect position between the rings 140 and 141.

The central transfer pipes 82, 100 and 116 are thus all directly supported upon the tubular shaft 85. Such a support is not practical or available for the annular transfer pipes 118 and 125 since they must rotate about the respective extensions 79, 94 and 110. To hold them for such rotation, the parts of annular transfer pipes 118 are supported by rollers 139 on hanger arms 136, which

hanger arms are secured to the respective brace bars 39, 40, 41 and 42.

The annular transfer passageway 125 has its upper edge 127 located to pass below the hangers 136 and rollers 139 carried thereby so that it may rotate freely under them. It is supported by hangers 142 extending from cross bars 143 across the corners of frame members 15, 16, 17 and 18, which arrangement of cross-bars is expanded in size to take care of the larger sized three-transfer-pipe distributor as a whole, as shown in Fig. 12.

The rollers 139 are held in an annular groove formed on the outside of wall 126 of annular passageway 125 by means of rings 144 and 145, Fig. 7, which are rigidly attached to the outside of wall 126 in the same manner that rings 140 and 141 are correspondingly attached to the outer surface of wall 118'.

Since the various transfer spouts are all subject to rotation, it is necessary to find means for locking them in any of their selected positions. Not only should the several transfer spouts be locked in proper delivering position facing an outlet hopper, but where a plurality of said spouts are employed, under the principle of my invention, they should be capable of being locked either one, several or all to discharge into one outlet spout. I accomplish this in the following manner.

For the center transfer spout I provide a drum 146, Figs. 2 and 7, supported at the center of radius bars 92, and having therein a suitable number of holes 147 cooperating with a catch rod 148, Fig. 2, which extends through the arms of a U-piece support 149 fast on the frame and which is pressed inwardly by compression spring 150 operating between a plate 151 on the rod 148 and a U-arm 152 on the U-piece 149.

Connected with an eye piece 152 on the rod 148 is a cord 154 which goes through casing 12 and is adapted to be extended over a pulley 155 supported on the outer side of casing 12a and over another pulley or pulleys 156 to a foot pedal 157 located at a convenient point on a floor 158, Fig. 9.

The drum 146 is formed with a suitable annular guideway 159 over or about which runs a cord 160. Parts of the opposite ends of this cord 160 run over pulleys 161 and 162 on the outside of casing wall 12, thence over one or more pulleys 163 and 164 to and over a pulley wheel 165, Fig. 9, which has a scale on the face of it, as shown, the perimeter of the scale cooperating with a pointer 166.

In operation the wheel 165 and the scale thereon are turned to bring the pointer 166 opposite any numeral, as the numeral 4 on said scale. The central spout member will then have its opening presented to the opening 75 of outlet hopper 66 corresponding to the numeral 4. By this means an operator who has pressed down on foot pedal 157 will release the central transfer spout for rotation. Then by rotating it he will bring it to discharge into the outlet hopper leading to a selected bin spout, after which, by releasing the rod 148, with very slight manipulation it can be made to lock the transfer spout in the selected position.

Similarly the annular transfer spout 102 (or 118) and 125 may be operated in the same manner. Thus for 102, as shown in Fig. 2, locking holes 167 are formed in the upper portion of the wall 118'. A detent 168 is supported by a U-piece 169 with a spring 170 tending to force the de-

tent through the holes 167 and a cord 171 running over pulleys 172, then carried over suitable intervening pulleys to a foot lever similar to foot lever 157.

An annular guideway is formed by a ring 173 fast on the outside of cylinder wall 148 and spaced from ring 141, Figs. 2 and 7, in which guideway runs a cord 174 which is carried by a pulley arrangement similar to that shown in Fig. 9 to an operating wheel similar to wheel 165 by means of which the transfer spout 107 (or 148) may be positioned and locked in position to deliver to a selected one of the outlet hoppers 66, in the same manner as shown in Fig. 7.

Openings 175 are formed in the outer wall of cylinder 126 and are entered by a rod 176 supported in a U-piece 177 and controlled by a spring 178 with a cord 179 running over a pulley 180, which, through appropriate intervening pulleys, runs to a wheel similar to wheel 165, whereby the outer transfer spout 125, when properly positioned by wheel like 165, may be locked to deliver to any selected outlet shoe.

In every form of my device—that is with any number of outlet members operative therein—there will always be formed in the top 13 an air outlet opening connected with a spout such as shown at 181 in Figs. 2 and 5. This has an important function not found in other distributors.

It is usually, or at least often, true that grain or other material is fed from the leg spout into the distributor chamber under or accompanied by considerable air pressure. The distributor chamber itself has been in the past sealed airtight or substantially airtight, and the bins which receive the grain and the bin spouts as connected with the transfer spouts in the distributor have also been sealed airtight.

It follows that as the grain or other material is transferred to the bin, air therein is displaced in bulk equal to the grain or other material being stored in the bin. Necessarily the air backs up through the bin spout into the distributor chamber. This builds up a pressure within the distributor chamber. The air under pressure usually escapes through small leaks in the system carrying with it fine dust which goes into the cupola and elevator loft and elsewhere and may create a serious fire hazard.

Also this air pressure in the distributor chamber may back up into the air leg and affect adversely the delivery of grain to such an extent as to produce clogging of the system.

The opening 181 not only relieves the air pressure in the distributor chamber by permitting the displaced air to flow out, but that air carries with it fine dust and other fine material which it is desirable to eliminate from the stored grain. This gives the important additional functions of effecting a degree of grain cleaning and of keeping dust from the cupola and other parts of the elevator, and thus eliminating the resulting fire hazard.

In connection with this feature of my invention there is very great value where an open-topped transfer spout is employed, such as transfer spout 82 of Fig. 5. When the material being distributed is a product such as ground feed, this does not flow freely and usually requires some degree of air pressure back of it, and the relief of this air pressure as well as that produced by displaced air from the bin and removal of very fine dust with the air, not only facilities

the operation of moving the feed to an appropriate bin, but tends to clean out undesirable detritus and dust that otherwise would go to the bins with the grain or feed.

In the invention as shown in Fig. 5, the open-topped spout 82 discharges to a single outlet member 66. Likewise, as shown in Fig. 2, the two transfer spouts 98 and 107 discharge one above the other into a somewhat larger outlet member 66', and in Fig. 7 the outlet spouts 112, 118 and 125 all discharge one above the other into the long outlet member 115.

Fig. 9 illustrates the position for discharge of central outlet spout 100 into one member while 15 annular outlet spout 108 is positioned for discharge into another outlet member 66'; and, as heretofore stated, no matter how many transfer spouts there may be (the central spout and surrounding annular spouts), as for example 20 three such spouts shown in Fig. 7, they all may discharge into a selected outlet member, and each at the same time may discharge into separated selected outlet members.

The several outlet members 66 and 66' shown 25 in Figs. 2, 5 and 6, and 115 shown in Fig. 7, are connected with bin spouts 182, as shown in full and dotted lines in Fig. 2. These bin spouts are removably supported by means of a latch 183 pivoted thereto at 184 and going over a catch 185.

30 When it is desired to remove one or more outlet members for repair or for other reasons the bin spout 182 is unlatched and pulled down slightly, the nuts 65 are turned to drop the lower cylinder 12a, the bolts 16 are removed which hold the outlet member being taken out to the adjacent outlet members, whereupon the outlet member may be lifted by shifting to the dotted line position of Fig. 2 and readily withdrawn.

In taking out one or more of the outlet members, in order to remove the screw bolts 76 which 40 secure the sides of the outlet members together it will be necessary to remove the conical bottom hopper 45, but, as stated above, this can be accomplished very easily. It thus is a simple 45 matter, which can be accomplished in a minute or two, at any time, to remove one or more of the outlet members and replace them with other members. This is an important feature of my invention since these members undergo heavy 50 wear from the impact of the flow of grain against them and quite frequently have to be removed and replaced.

It frequently happens that when grain has been 55 discharged through a distributor from the bin spout to a bin in the elevator, the bin may fill up before the operator realizes it. When that has occurred with other grain distributors, the grain backs up in the bin spout and ultimately fills the distributor chamber and even backs up the leg spout and usually produces a great deal of spillage, and always this has caused much expense and loss of time to remedy the clogging of the distributor system.

In my construction, when this happens the 60 grain will back up in the bin spout 182 into an outlet member 66, 66' or 115. But immediately it flows from the lower part of the outlet member into the conical hopper 45 and through the opening 46 and down the spout 186, Figs. 2 and 7.

65 This spout passes it back to the bottom of the elevator where loading of the elevator leg is taking place, thus preventing filling of the distributor chamber, clogging of the system and spillage of grain which otherwise would take place. For 70 the grain remaining in the bin spout is unimper-

tant because it will gravitate into the bin with which it is connected whenever grain has been removed from that bin.

The end of transfer spout bottom 82, 100 or 116 each comes somewhat above the bottom 69 of the outlet member, and the bottoms 82, 100 and 117 are each cut away as indicated at 84 and 117, which gives ample space for grain to flow from the filling outlet member to the hopper 45 and thence back to the loading bin or boot.

The advantages of my invention will sufficiently appear from the foregoing description. These advantages comprise adaptability to operate in connection with one, two, three or more elevator legs, thus greatly increasing the capacity of the distributor; simplicity of arrangement of outlet members so they will be highly effective to receive grain from the transfer spouts when positioned in respect to any of them, and will be particularly adapted to prevent spillage of grain in the event that a bin and spout become filled; also as to the outlet members the remarkably advantageous facility and ease with which they may be installed and removed; the simple but effective arrangement for rotating the transfer spouts, with the supporting shaft having the central transfer spout supported directly thereby, and each annular transfer spout supported by hangers and rollers, which, having an annular chamber for receiving the leg discharge spout, are always connected therewith without the necessity of using valves or other shifting means; the pressure relief opening to the distributor chamber which peculiarly adapts the distributor for use when the grain and particularly when feed is delivered against air pressure from displaced air from the bin or from forced air-feeding of the grain; the practical means for rotating each of the transfer spouts independently of the other and of setting them in definitely fixed relation to a selected outlet member; and the feature of collecting and returning overflow from any filled bin and bin spout to the loading bin or boot.

All these features are in a high degree efficient and useful in the construction and operation of my grain distributor. These features are of such nature that not only is my distributor remarkably efficient but provides low cost of manufacture and upkeep. This is assured, because both weight and volume or bulk of the distributor is small in proportion to its capacity for serving many outlet members and bin spouts. Further, that small volume enables the distributor to be put in small cupolas, in many elevators a matter of great importance.

In small elevators it quite frequently happens that, in order to handle the incoming grain with greater facility, an additional elevator leg or legs will be installed. Heretofore when this is done in many cases it has been necessary to raise the cupola or even to raise and enlarge it. Another highly important advantage of my invention comes from the fact that, in practically all such instances, by the use of my distributor the additional elevator leg or legs can be installed without raising the cupola or increasing its size.

I claim:

1. A grain distributor, comprising two cylindrical casing members of the same diameter, means adjustably holding the two members with their surfaces coaxial and their adjacent edges suitably spaced apart, and a multiplicity of outlet members removably held between said edges

so as to form a complete circumferential series of said outlet members.

2. A grain distributor, comprising two cylindrical casing members of the same diameter, means adjustably holding the two members with their surfaces coaxial and their adjacent edges suitably spaced apart, a multiplicity of outlet members removably held between said edges so as to form a complete circumferential series of said outlet members, and a transfer spout within said casing member adapted to be connected with the discharge spout of an elevator leg and having its discharge end positioned to coincide with a part of the opening into an outlet member.

3. A grain distributor, comprising two cylindrical casing members of the same diameter, means adjustably holding the two members with their surfaces coaxial and their adjacent edges suitably spaced apart, a multiplicity of outlet members removably held between said edges so as to form a complete circumferential series of said outlet members, and a transfer spout within said casing member adapted to be connected with the discharge spout of an elevator leg and having its discharge end positioned to coincide with a part of the opening into an outlet member, said transfer spout being mounted for rotation to cause its opening to coincide with the opening of any selected outlet member.

4. A grain distributor, comprising two cylindrical casing members of the same diameter, a set of supporting rods having connection with the two cylindrical members and bridging the space between their adjacent edges, means on the rods for changing the width of the space between said edges, and a multiplicity of outlet members removably held between said edges so as to form a complete circumferential series of said outlet members, said outlet members being formed with parts engageable with the respective edges so drawing the edges together to clamp all said outlet members in operative position.

5. A grain distributor, comprising two cylindrical casing members of the same diameter, means adjustably holding the two members with their surfaces coaxial and their adjacent edges suitably spaced apart, a multiplicity of outlet members removably held between said edges so as to form a complete circumferential series of said outlet members, and an open-topped transfer spout within said casing members adapted to be connected with the discharge spout of an elevator leg and having its discharge end positioned to coincide with a part of an opening into an outlet member.

6. A grain distributor, comprising two cylindrical casing members of the same diameter, means adjustably holding the two members with their surfaces coaxial and their adjacent edges suitably spaced apart, a multiplicity of outlet members removably held between said edges so as to form a complete circumferential series of said outlet members, a transfer spout within said casing members adapted to be connected with the discharge spout of an elevator leg and having its discharge end positioned to coincide with a part of the opening into an outlet member, and a cover member secured to the edge of one of said casing members, said cover having an opening for discharge of air under pressure and dust carried thereby.

7. A grain distributor, comprising two cylindrical casing members of the same diameter, means adjustably holding the two members with their surfaces coaxial and their adjacent edges

suitably spaced apart, a multiplicity of outlet members removably held between said edges so as to form a complete circumferential series of said outlet members, a transfer spout within said casing members adapted to be connected with the discharge spout of an elevator leg and having its discharge end positioned to coincide with a part of the opening into an outlet member, and a conical hopper forming the bottom of the chamber formed by the casing members and having a central opening for receiving and discharging through said opening overflow grain backed up through any of said outlet members.

8. A grain distributor, comprising a casing member formed of two separable portions, means adjustably holding the two portions with their

surfaces coaxial and their adjacent edges suitably spaced apart, and a plurality of outlet members replaceably held between the separable portions of the casing member.

5 ROY I. PATTERSON.
